FIG. 3.

FIG. 2.

Perry Miller

UNITED STATES PATENT OFFICE.

PERRY MILLER, OF ALGER, OHIO.

ONION TOPPER.

Application filed March 7, 1923. Serial No. 623,468.

To all whom it may concern:

Be it known that I, PERRY MILLER, a citizen of the United States, residing at Alger, in the county of Hardin and State 5 of Ohio, have invented certain new and useful Improvements in an Onion Topper, of which the following is a specification.

This invention relates to an onion topper, and has for its prime object to provide a 10 topper constructed on the principle of a pair of shears, which will quickly and readily sever the heads from the onions prior to crating of same for market.

A further object of the invention is to 15 provide an onion topper of the above indicated character, which can be quickly and readily secured in position to the side of a crate, and which is automatic in operation upon bringing of an onion into engagement 20 with the shear-like blades.

A still further object of the invention is to provide an onion topper of the above indicated character, which is simple in construction, durable, efficient for the purpose 25 intended, and one that can be manufactured and sold at a relatively low cost.

These and like objects of the invention will be better understood as the description follows and as is specifically pointed out in 30 the appended claims.

Referring to the accompanying drawings which form a part of this specification,

Figure 1 is an end elevation of an onion topper constructed in accordance with my 35 invention, showing same applied to the side of a crate.

Figure 2 is an end elevation of my top- 40 per removed from the side of the crate.

Figure 3 is a front elevation of an onion topper constructed in accordance with my 45 invention.

Figure 4 is a top plan view of same, and

Figure 5 is a sectional view taken on line 5-5 of Figure 3, looking in the direction 45 of the arrows.

Referring to the accompanying drawings in detail, like characters will be used to designate like parts in the different views.

In the drawings, the numeral 1 indicates 50 a crate to which my improved onion topper is adapted to be connected.

My improved onion topper comprises a plate 2 having a spring clip 3 attached to one side of same at opposite ends, as is 55 clearly shown in Figure 3 of the accompanying drawings. It is to be understood that

the spring clips 3 are attached to the plate 2 in any suitable manner.

A pair of shear-like blades 4 having op- 60 posing cutting edges 5 are adapted to be connected to the upper edge of the plate 2 on the opposite side of same to which the clips 3 are connected.

One of the shear-like blades 4 is rigidly secured to the upper edge of the plate 2 65 by bolts 6, while the opposite blade is rigidly secured to the middle of the plate by one of the bolts 6, but the said blade is per- mitted a limited movement by being pro- vided with an arcuate slot 7 adjacent one 70 corner of same, through which passes a fastening bolt 8.

A fastening bolt 6' has a spring coiled around same as at 9, and the spring has two 75 diverging arms 10 and 11, which are spaced away from the shear-like blades 4. The upper portion of each of the arms 10 and 11 are bent inwardly as at 12 and are adapted to pass through an eye 13 in the blades and the free end of each of the wires 80 is turned upwardly as at 14 for securely locking same in position. Thus it can be readily seen that the tension of the spring around the bolt 6' and the outwardly diverg- 85 ing arms will force the cutting edges 5 into engagement with each other.

When an onion is placed between the blades and moved downwardly against the cutting edges 5, same will be readily severed.

In view of the foregoing description of 90 my invention, taken in connection with the accompanying drawings, it is thought that any further explanation as to the construction, operation, and objects of the invention is unnecessary.

While I have shown and described the preferred form of my invention, I realize that various minor changes may be resorted to, without departing from the spirit and scope of the invention as claimed, and therefore, I do not wish to limit myself to the exact details of construction shown, nor to the combination and arrangement of parts.

What I claim as new and desire to secure by Letters Patent is:

1. In an onion topper, a base having a pair of spring clamping arms for engagement with said support, shear-like blades having beveled cutting edges secured to the upper edge of said base, a coil spring se- 110 cured to said base and having diverging arms connecting said shear-like members

adjacent their pointed ends for moving the cutting edges of said shear-like blades into engagement with each other.

2. An onion topper of the class described comprising a base plate, a pair of spring clamping arms being secured to said plate, a pair of shear-like blades having opposed cutting edges, means for rigidly connecting said blades to the base plate, one of said blades having an arcuate slot formed therein, a fastening bolt passing through said slot for limiting the movement of the blade.

3. An onion topper comprising a base plate, a pair of spring clamping arms connected to the latter, shear-like blades having opposed cutting edges secured to the upper edge of the base plate on the opposite sides to which the spring arms are connected, one

of said blades having an arcuate slot formed therein and a fastening bolt passing through said slot for limiting the movement of the plate, a coil spring including diverging arms which are suitably spaced from the shear-like blades, the upper portion of said arms being bent inwardly and designed to pass through an eye formed in the blade, the free ends of each of the wires being turned upwardly for securely locking the same in position.

In testimony whereof, I have affixed my signature in the presence of two witnesses.

PERRY MILLER.
